US0D1067255S

(12) **United States Design Patent** (10) Patent No.: **US D1,067,255 S**
(45) Date of Patent: ** Mar. 18, 2025

(54) **DISPLAY SCREEN WITH GRAPHICAL USER INTERFACE**

(71) Applicant: **NEC Corporation**, Tokyo (JP)

(72) Inventors: **Ayaka Amakawa**, Tokyo (JP); **Maki Sano**, Tokyo (JP)

(73) Assignee: **NEC CORPORATION**, Tokyo (JP)

(**) Term: **15 Years**

(21) Appl. No.: **29/913,514**

(22) Filed: **Oct. 3, 2023**

(30) **Foreign Application Priority Data**

Apr. 11, 2023 (JP) ..... 2023-007421 D

(51) **LOC (15) Cl.** **14-04**

(52) **U.S. Cl.**

USPC **D14/485**

(57) **CLAIM**

The ornamental design for a display screen with graphical user interface as shown and described.

DESCRIPTION

The file of this patent contains at least one drawing executed in color. Copies of this patent with color drawing(s) will be provided by the Office upon request and payment of the necessary fee.

The sole FIGURE is a front elevational view of a display screen with graphical user interface showing our new design.
